UNITED STATES PATENT OFFICE.

JAMES J. FAULKNER, OF MEMPHIS, TENNESSEE, ASSIGNOR TO THE STANDARD COTTON SEED COMPANY, OF ARKANSAS.

COTTON-SEED DELINTER.

SPECIFICATION forming part of Letters Patent No. 550,222, dated November 19, 1895.

Application filed September 16, 1895. Serial No. 562,642. (No model.)

To all whom it may concern:

Be it known that I, JAMES J. FAULKNER, a citizen of the United States, residing at Memphis, in the county of Shelby and State of Tennessee, have invented certain new and useful Improvements in Cotton-Seed Delinters; and I do hereby declare the following to be a full, clear, and exact description of the invention, such as will enable others skilled

in the art to which it appertains to make and use the same.

My invention relates to improvements in machines for treating cotton-seed, and particularly to improvements in that class thereof known as "delinters;" and it consists in the improved cotton-seed delinter whose construction and arrangement of parts will be hereinafter fully described, and particularly pointed out in the claims.

One of the well-known types of cotton-seed delinters is that which is commonly termed the "arm" delinter—that is to say, a cotton-seed delinter in which the rotating abrading-surfaces consist of a number of arms mounted upon a power-shaft and either formed of abrading material or having sections of abrading material secured thereto. This type of cotton-seed delinters has for a long time been popular; but the development of a practical machine of this type has been retarded by the difficulty of providing the details of construction necessary to secure a successfully operative machine.

The advantages offered by the arm type of cotton-seed delinters are great and are readily apparent upon a consideration of the fundamental principles of operation which control the action of all machines for delinting cotton-seed.

It is a well-known fact that cotton-seed while under treatment in a cotton-seed delinter assumes the form of a roll around the inner surface of the delinting-cylinder casing, which roll has a rate of rotation entirely independent of the rate of rotation of the abrading-surfaces. To secure the best results the abrading-surfaces should be formed not only so as to scour the surface of the seed, but also so as to interrupt and vary the formation of the roll of seed, so that new faces thereof may be continually presented to the abrading ac-

tion. It is apparent that the greater the number of abrading contacts the seed receives while under treatment in the machine the more complete must be the removal of the lint from the surfaces thereof. Only a momentary contact of the seed with the abrading-surfaces is necessary in order to scour from the face presented all the lint which adheres thereto.

In the arm type of cotton-seed delinters, where the abrading-surfaces only extend over a relatively small segment of a circle, it is apparent that every advantage is present for securing a number of distinct abrading contacts upon the surface of the seed under treatment, and, further, that the duration of the abrading contacts will only be long enough to enable sufficient scouring action to take place to remove the lint from the surface of the seed presented to such action.

In considering the formation of abrading-surfaces it should also be remembered that the abrading action which takes place is due simply to the difference between the rate of rotation of the abrading-surfaces and that of the roll of seed. All the power necessary to cause the seed to assume a centrifugal movement and to cause the abrading-surfaces to rotate as rapidly as the roll of seed is lost for the delinting operation, and only the energy expended in causing the abrading-surfaces to rotate more rapidly than the roll of seed is available therefor. This fact enters as a prominent factor in determining the character and relative efficiency of abrading-surfaces.

The arm type of cotton-seed delinters is especially adapted to expedite the formation of the roll of seed in the machine and the imparting thereto of the requisite centrifugal movement, and, further, offers the advantage of involving a minimum amount of frictional loss due from the compression which it is necessary to exert on the roll of seed in order to secure a satisfactory delinting operation. In spite of these advantages few or no constructions have been devised for holding in proper position for effective action the sections of emery which constitute the revolving abrading-surfaces of this type of machine, and difficulty has always been experienced in

removing the lint as rapidly as it is scoured off the surface of the seed under treatment—a function which must necessarily be performed if the abrading-surfaces are not to be 5 clogged and dulled by the lint which they remove from the seed.

The objects of my invention are, first, to provide an improved means for holding the blocks of emery in position for effective action 10 on the ends of the abrading-arms and to provide an improved form of abrading-block especially adapted for this type of construction, and, second, to provide an improved device for effecting the removal from the machine 15 of the lint scoured off the surface of the seed under treatment.

In accomplishing the first-stated object of my invention I form chambers or recesses in the ends of each of the abrading-arms and secure 20 in the same the emery blocks which are to constitute the active abrading-surface. The ends of the abrading-arms may be bent into any shape desired, such as an upwardly-curved shape, which I herein illustrate and 25 which has proven one of the best forms of abrading-surfaces for treating cotton-seed, and the blocks can be held in position in the chambered ends of the arms either by the application of glue or cement or by the use of 30 additional holding means, such as bolts or rivets. The blocks are not liable to wear or breakage, and they can be easily removed and replaced in case of accident. A single block may be made large enough to completely 35 fill the hollow end of a single arm, or a number of blocks may be used with a single arm, this being a detail of construction which is immaterial and may be varied as desired. The upper or active surface of the abrading-blocks 40 may be given any form or configuration desired; but I prefer to round the lower portion thereof—that is to say, the portion which is held in the hollow end of the abrading-arms—and to form a groove at the point of 45 junction of the upper and lower portions of the block, so as to enable the holding means to obtain a more effective grip thereon. I have also devised an improved construction for facilitating the removal of the lint, which 50 is scoured by the action of the machine from the surface of the seed under treatment, from the inclosure in which the abrading action takes place.

In an application for Letters Patent filed 55 by me May 20, 1895, Serial No. 549,980, I have described a moving lint-removing device consisting of a series of rotating saws stationed in the open mouth of an air-flume, which is in free communication with the abrading-surfaces 60 through an opening in the casing thereof, journaled with a portion of their peripheries projecting through said opening and operating to catch and remove the lint which is scoured from the surface of the seed. In 65 said application I have stated that it is necessary for the satisfactory operation of this type of lint-removing devices that the air-

current have free access to the abrading-surfaces over the entire length of the opening formed in the delinting-cylinder casing as it 70 acts in connection with the saws to remove the lint.

In the machine which forms the subject-matter of the present application I use as a 75 lint-removing device, instead of a series of saws, a cylinder having a perforate periphery stationed, as before, in the mouth of the air-flume, which is in communication with the abrading-surfaces through an opening in the delinting-cylinder casing, and journaled so 80 that a portion of its periphery extends through said opening and comes into close relation with the abrading-surfaces. The lint, as rapidly as it is scoured off the surface of the seed under treatment, is swept upon the 85 periphery of the cylinder by the force of the air-current which sweeps through the perforations of the same, and is removed from the inclosures in which the delinting operation takes place by said cylinder as it completes its revolution. The lint removal thus effected is positive in its action and is very 90 satisfactory. In this type of lint-removal construction the opening formed in the delinting-cylinder casing to permit the removal of lint 95 usually extends the entire length of the machine, and I have found it necessary to provide means for preventing the spreading of the edges of the opening and the consequent escape of the seed. With this end in view I 100 form the lint removing or gathering cylinder in sections and brace the edges of the opening in the casing by securing thereto supports, which pass between the sections of the lint-removing cylinder. These supports serve the 105 further function of spacing-ribs to prevent the discharge of seed between the sections of the lint-removing cylinder. In the use of this form of lint-removing cylinder I secure the further advantage of automatically freeing the same from the dirt which gathers in 110 the interior. This dirt of itself gravitates to the ends of the sections of the cylinder and is there subjected to the action of the air-current existing in the lint-discharge flume. The 115 surface of the lint-removing cylinder is thus kept free from the accumulation of dirt and is at all times in condition for effective action. In this type of lint-removing device it is advantageous to have as large a portion as possible of the surface of the lint-removing cylinder in communication with the abrading-surfaces through the opening in the casing therefor. With the ordinary construction of 120 casing, however, only a small portion of the periphery of the lint-removing cylinder can project through the opening in the casing without conflicting with the movement of the revolving abrading-surfaces. To increase the amount of available active lint-removing surface, I form the upper portion of the casing for 125 the abrading-surfaces eccentrically to the line of motion of the rotating arms, and form the opening in the casing through which the lint- 130

removing action takes place at the top of the casing, so that at this point the lint-removing cylinder can be journaled with a much larger portion of its periphery extending into the inclosure in which the delinting operation takes place than would otherwise be the case. The lint-removing action is thus facilitated and a smoother and more uniform operation of the machine obtained.

10 My invention is fully represented in the drawings which accompany and form a part of this application, in which the same reference letters and numerals refer to the same or corresponding parts, and in which—

15 Figure 1 is a vertical section of my machine, showing the relation the various parts bear to each other, the arms which hold the abrading-sections being shown as secured to a hollow cylinder supported upon the central shaft. Fig. 2 is a longitudinal section of the machine, showing especially the form of lint-removing cylinder, another form of support for the abrading-arms being represented. Fig. 3 is a detail view of one of the arms bearing the abrading-blocks, the blocks themselves being shown above the recessed portion of the arm. Fig. 4 is a cross-section of an abrading-block and the arm bearing the same.

20 Referring to the drawings, A represents the machine-frame. This frame forms a support for the casing B, which is provided for the abrading-surfaces and which forms the inclosure within which the entire delinting action of the machine takes place, and also has bearings therein for the main power-shafts of the machine—namely, the shaft C, which extends centrally through the casing and has mounted thereupon the arms D, bearing on their outer 25 ends the abrading-sections E, and the shaft F, upon which is mounted the seed feeding or conveying device. Shaft G, which is stationed at the top of the machine and has mounted thereupon the lint-removing cylinder H, is not journaled directly in the machine-frame, but is supported in bearings secured to the upper surface of the casing B. The shaft G is rotated by a direct gearing connection 1 with the central power-shaft C, 30 while shaft F, upon which the seed feeding or conveying device is mounted, is rotated by a sprocket connection 2 with the end of the shaft G opposite to that to which power is imparted.

35 In the construction and operation of cotton-seed delinters it is necessary to provide means for, first, feeding the seed into the machine uniformly and conveying the seed from the inlet to the discharge-opening regularly at a

40 rate of speed dependent upon the rapidity of the delinting operation; second, for scouring or abrading the surface of the seed under treatment in order to remove therefrom the lint which adheres thereto and which it is the 45 purpose of the operation to separate from the seed, and, third, to remove the lint from the inclosure in which the delinting operation

takes place as rapidly as it is scoured off the surface of the seed under treatment.

In the consideration of my present machine 70 the parts thereof will be described in the order indicated, and then the operation of the machine as a whole will be considered.

I. Feeding and Conveying of the Seed.

75

The seed is fed into the machine through an opening I, formed in the end of the casing J, which casing is supported directly under the casing for the abrading-surfaces and is perforated to permit free passage of air upward 80 into the inclosure in which the abrading action takes place through an opening formed in said casing for the abrading-surfaces. This opening extends the whole length of the casing for the abrading-surfaces and permits 85 free communication between said casing and the casing J, supported beneath the same. Within the casing J is journaled the shaft F, upon which are mounted the spiral conveyer K, stationed directly under the feed-opening, 90 and the pins or spikes L, which are scattered over the entire length of the shaft not occupied by the conveyer K and act to stir the stock and promote its passage through the machine. The seed fed to the machine through 95 the feed-opening I is thus positively conveyed through the same, and the conditions are such that a uniform rate of travel is given thereto. Such seed is constantly caught up by the abrading-surfaces and is subjected again and 100 again to the abrading action taking place within the casing, so that as it is finally discharged through the valved discharge-opening M it is entirely freed from lint and in marketable condition. The perforations in 105 the casing J serve to permit the passage of currents of air, which act to cool the seed under treatment, to assist in the separation therefrom of the fine lint, which, even after it is scoured from the surface of the seed, 110 might otherwise tend to cling to the same, and also permit the escape of much of the dirt which is present with the seed as it is subjected to the delinting operation. Within 115 the casing there is further effected a gradation of the seed under treatment, the clean seed falling to the bottom of the casing and being swept along the bottom to the discharge-opening, while the uncleansed seed, by reason of its lighter specific gravity, remains on the 120 surface of the seed within the casing and is continually caught up by the rotating abrading-surfaces and resubjected to the abrading action.

II. The Abrading-Surfaces.

125

The abrading-surfaces of this machine consist of the sections of abrading material E, secured to the ends of the arms D, and the abrading-surfaced lining of the casing B. These 130 arms may be secured to a hollow cylinder C', which is mounted upon the central shaft and rotates therewith, as shown in Fig. 1, or they may be formed as arms of spiders having a

common hub, as shown in Fig. 2, or any other suitable construction may be used for securing them in position in the machine. The lining of the casing may be of any ordinary construction and may have either a smooth or roughened exterior, in accordance with the desire of the operator. The method of holding in place the abrading-blocks N, which constitute the abrading-sections E, and the form of said blocks are, however, novel and demand detailed description.

The abrading-blocks N are formed with a rounded upper surface n and an undercut rounded lower portion n' , a groove n^2 being formed at the point of meeting of the upper and lower portions of the block. This construction is especially adapted to enable the blocks to be held firmly in place in the chambered or recessed ends of the arms D. The ends of the arms D are bent into the form shown in the drawings, so that they present an upwardly-rising curved portion. They are hollowed out to afford a recess or chamber in which the abrading-blocks may be held. The arms D are preferably made of pipe, and the section of the pipe cut therefrom to form the opening which permits the entrance of the abrading-blocks is cut above the center of the pipe, so that the edges of the opening formed curve inwardly in a position to enter the grooves formed in the abrading-blocks, and thus to constitute an active retaining means. At their inner ends the openings formed in the ends of the arms gradually narrow in width, and for this portion of the groove the section of abrading material used is formed with special reference thereto, as shown in Fig. 3. The blocks may be held in position in the ends of the arms by means of glue or cement; but I preferably use additional holding means, such as the rivet n^3 shown in the drawings. The blocks are not liable to excessive wear and are not readily broken; but in case they are broken they can be taken out and replaced with a minimum amount of trouble. The blocks may be made of such a size that a single block will fill the recess formed in the ends of each of the arms D, or a number of blocks, as shown, may be used for each arm.

To facilitate the repair of the machine, I have supported the arms D in such manner as to permit their ready removal, either holding them by means of thumb-screws in sockets formed on a hollow cylinder mounted upon the central shaft or forming each cylindrical series of arms with a common hub, as shown in Fig. 2. In the former construction, should one of the blocks in one of the arms become broken the entire arm can be readily removed and a new arm put in position. By undercutting the lower portion of the abrading-block an overhanging ledge is formed which prevents any portion of the abrading-arms coming in sufficiently close contact with the seed under treatment to damage the same. The entire abrading-surface is that formed by the

upper surface of the abrading-blocks, and this may be made smooth or roughened, in accordance with the finish given to said blocks 70 or the form of the upper surface chosen.

The lower half of the casing for the rotating abrading-surface is concentric with the movement of the same, the distance between the inner surface of the casing and the ends 75 of the arms being about five-eighths of an inch, that having been found a satisfactory distance for delinting purposes. The upper half of the casing for the abrading-surfaces is, however, eccentric to the line of movement 80 of the abrading-surfaces, in that the distance between the end of the abrading-arms and the inner surface of the casing gradually increases until the top of the casing is reached. The reason for so forming the casing will be apparent when the lint-removing action is considered. The effect upon the seed under treatment is to diminish at the upper portion of the casing the density of the roll which the seed forms in the machine, and of course to 85 decrease the efficiency of the delinting operation at this point—a disadvantage which is, however, far more than counterbalanced by the gain in efficiency of the lint-removing action. 95

III. The Lint-Removal Device.

To remove the lint from the abrading-surfaces as soon as it is separated from the seed by the action of the machine, I form in the center 100 of the upper portion of the casing an opening P, which extends longitudinally of the casing, and support, in connection with this opening, the open end of the air-flume Q, in which an outward current of air is caused to exist by 105 an exhaust-fan, (not shown), and in which is journaled the lint-removing cylinder H. By reason of the eccentric formation of the casing B the cylinder H is enabled to be journaled with a considerable portion of its periphery projecting into the inclosure in which the delinting operation takes place without interfering with the revolution of the abrading-arms. The active lint-removing surface is thus markedly increased, and the lint is 110 removed from the abrading-surfaces rapidly and efficiently. The lint-removing cylinder 115 H may be formed either of wire mesh or of perforate iron.

It is essential to the successful operation of 120 the lint-removing action that air have free access to the abrading-surfaces, and as the periphery of the cylinder works through the opening in the casing so as to come into intimate relation with the abrading-surfaces, 125 some perforated formation is necessary. The draft of the air-current, which draws its supply through the perforations in the casing J, causes the lint which is separated from the seed to be swept against the surface of the 130 lint-removing cylinder and to be removed as the cylinder completes its revolution from the inclosure in which the delinting operation takes place. The lint is doffed from the cyl-

inder by the doffing-brushes S and is drawn outward into the discharge-flume.

The action of the doffing-brushes is made possible by the upward air-current which exists in the lint-discharge flume, and takes place in spite of the fact that the doffing-brushes are stationary.

On account of the length of the longitudinal opening formed in the casing, it is essential that some means be used to prevent the opening spreading and permitting escape of seed at this point. Should such spreading take place, the efficiency of the machine would be very much decreased by the resultant loss of product. With a view to preventing the spreading of the sides of this opening, I form the lint-removing cylinder in sections, as shown in Fig. 2, and between the adjacent ends of the sections of the cylinder I pass rods or braces T, which are attached to the two sides of the longitudinal opening in the casing, and which are wide enough to prevent the escape of seed at these points.

The construction of lint-removing cylinder which I have made use of is adapted to free the interior of the cylinder from the fine dirt which gathers therein in the action of the machine, as such dirt will naturally gravitate toward the openings at the ends of these various sections and will be drawn outward by the air-current. The gathering-cylinder itself is made of a series of hubs h, which point inward in pairs, over which are slipped the wire mesh or perforated iron cylinders to be used.

To further assist in the prevention of loss of stock through the opening in the top of the casing B through which the lint-removing cylinder operates, I provide said lint-removing cylinder on one side thereof with an adjustable guard-plate U, which is journaled in the air-flume Q upon a revoluble pin q and extends longitudinally of the lint-removing cylinder. This guard-plate extends downward into the inclosure in which the delinting operation takes place and is provided with a V-shaped end u, which always effects a complete closure of the opening into the air-flume. Upon the pin q is rigidly mounted the outwardly-extending lever-arm V, whose upper surface is notched to permit adjustment thereon of the weight W. Means are thus provided for regulating the pressure with which the guard-plate bears against the surface of the lint-removing cylinder. If desired, a spring X may be used in addition to the means shown, or the spring construction may be relied upon entirely to effect the desired control of the guard-plate.

IV. Operation of the Machine.

The operation of my machine is as follows: Seed is fed into the machine through the feed-spout I and is fed through the machine by the spiral conveyer K. It is caught up again and again by the abrading-arms and subjected to the scouring action of the abrading-surfaces. When finally discharged through

the discharge-opening M in quantities regulated by its condition, the seed is entirely cleansed and freed from lint. The form of abrading-surfaces is such as to cause the roll of seed to assume the desired centrifugal movement with a minimum expenditure of power and to give the seed treated a large number of distinct abrading contacts, while avoiding undue frictional loss by reason of compression exerted upon the roll of seed. As rapidly as the lint is scoured from the surface of the seed under treatment, it is stripped against the surface of the lint-removing cylinder H and drawn out of the inclosure in which the delinting operation takes place, it being doffed from said cylinder by the doffing-brush S and swept into the air-flume Q. The guard-plate W, by reason of its constant pressure against the sides of the lint-removing cylinder, prevents escape of stock, but does not hinder the removal of lint. The air-current existing in the interior of the casing not only assists in the rapid removal of the lint as rapidly as it is scoured off the surface of the seed under treatment, but also assists in the prevention of the clogging of the rotating abrading-surfaces. The greater portion of the dirt which is always present with cotton-seed as it is subjected to the delinting operation escapes through the perforations in the casing.

I do not herein claim, broadly, a moving lint-removing device formed so as to permit free access of air to the abrading-surfaces and stationed in the open mouth of an air-flume which is in free communication with the abrading-surfaces through an opening in the casing therefor, as this forms the subject-matter of a separate application, filed by me May 20, 1895, Serial No. 549,980.

Having thus fully described my invention, what I claim as new, and desire to secure by Letters Patent, is—

1. In a cotton seed delinter, the combination with a suitable casing, and a shaft extending through the same, of a series of tubular arms mounted on said shaft, said arms having their outer ends bent and cut away on their upper sides above the center line of the tubular arms, and a series of sections of abrading material adapted to be held in the cut away portions of said arms, substantially as described.

2. In a cotton seed delinter, the combination with a suitable casing, and a shaft extending through the same, of a series of tubular arms mounted on said shaft, said arms having their outer ends bent, and cut away on their upper sides so as to form openings which become narrower as the inner ends of the cut away portions are reached, and a series of sections of abrading material adapted to be held in the cut away portions of said arms, substantially as described.

3. In a cotton seed delinter, the combination with a suitable casing, and a shaft extending through the same, of a series of tubu-

lar arms mounted on said shaft, said arms having their outer ends bent and cut away on their upper sides above the center line of the same, the openings formed becoming narrower as the inner ends of said cut away portions are reached, and a series of sections of abrading material adapted to be held in the cut away portions of said arms, substantially as described.

- 10 4. In a machine for delinting cotton seed, the combination with a casing having an opening therein, and means for causing the seed under treatment to assume a centrifugal movement within the casing, of an air flume 15 in communication with said opening, and a cylinder having a perforate periphery stationed in said air flume and so journaled that its periphery works through the opening in the casing, substantially as described.
- 15 5. In a machine for treating cotton seed, the combination with a casing having an opening therein, and a revolving abrading surface operating in the same, of an air flume in communication with said opening, and a cylinder 20 having a perforate periphery stationed in said air flume and so journaled that its periphery works through the opening in the casing, substantially as described.

- 25 6. In a machine for delinting cotton seed, the combination with a delinting cylinder, and a casing therefor having an opening therein, of an air flume in communication with said opening, and a cylinder having a perforate periphery stationed in said air flume, and so 30 journaled that its periphery works through the opening in the casing, substantially as described.

- 35 7. In a cotton seed delinter, the combination with a revolving abrading surface, and a casing therefor having an opening therein, of an air flume in communication with said opening, a sectional cylinder having a perforate periphery stationed in said air flume, and working through the opening in the casing to 40 remove the lint from the abrading surfaces, and means for preventing the discharge of seed into the air flume through the openings between the sections of the cylinder, substantially as described.

- 45 8. In a cotton seed delinter, the combination with a revolving abrading surface, and a casing therefor having a longitudinal opening formed therein, of an air flume in communication with said opening, a sectional cylinder 50 having a perforate periphery stationed in said air flume, and working through the opening in the casing to remove the lint from the abrading surfaces, and supports, extending between the edges of the longitudinal opening 55 in the casing, and passing between the sections of the sectional cylinder, substantially as described.

- 60 9. In a cotton seed delinter, the combination with a casing having an opening therein, and a revolving abrading surface operating in said casing, of an air flume in communication with said opening, a cylinder having a

perforate periphery stationed in said air flume, and working through the opening in the casing to remove the lint from the abrading surfaces, and a doffing brush for removing the lint from said cylinder, substantially as described.

70 10. In a cotton seed delinter, the combination with a casing, and revolving abrading surfaces journaled eccentrically within the casing, of an opening in the casing at that portion thereof at which the revolving abrading surfaces move farthest from its inner surface, and a moving lint removing device, journaled with a portion of its periphery projecting through the opening in the casing, substantially as described.

75 11. In a cotton seed delinter, the combination with a shaft, and a series of revolving abrading surfaces mounted thereupon, of a casing therefor whose upper surface is eccentric to the line of motion of the abrading surfaces, an opening in said upper portion of the casing, and a moving lint removing device 80 journaled with a portion of its periphery projecting through the opening in the casing, substantially as described.

85 12. In a cotton seed delinter, the combination with a shaft, and a series of revolving abrading surfaces mounted thereupon, of a casing therefor whose upper surface is eccentric to the line of motion of the abrading surfaces, an opening in the upper portion of said casing, an air flume in communication 90 with said opening, and a cylinder having a perforate periphery journaled in said air flume with a portion of its periphery projecting through the opening in the casing, substantially as described.

95 13. In a cotton seed delinter, the combination with revolving abrading surfaces, and a casing therefor having an opening therein, of a lint removing cylinder journaled with a portion of its periphery projecting through 100 the opening in the casing, a pivoted guard plate, and means for causing said guard plate to bear against the periphery of said cylinder, substantially as described.

105 14. In a cotton seed delinter, the combination with revolving abrading surfaces, and a casing therefor having an opening therein, of a lint removing cylinder journaled with a portion of its periphery projecting through 110 the opening in the casing, a revoluble rod extending lengthwise of the cylinder, a guard plate mounted thereon, a lever arm rigidly attached to said rod, and an adjustable weight held upon said rod for causing said guard plate to bear against the periphery of said 115 cylinder, substantially as described.

15. In a cotton seed delinter, the combination with revolving abrading surfaces, and a casing therefor having an opening therein, of a lint removing cylinder journaled with a portion of its periphery projecting through 120 the opening in the casing, a pivoted guard plate having a V-shaped end, and means for causing said guard plate to bear against the

periphery of said cylinder, substantially as described.

16. In a cotton seed delinter, the combination with revolving abrading surfaces, and a casing therefor having an opening therein, of an air flume in communication with said opening, a cylinder having a perforate periphery stationed in said air flume, and journaled with a portion of its periphery projecting through the opening in the casing, a pivoted guard plate, and means for causing said guard plate to bear against the periphery of said cylinder, substantially as described.

17. In a cotton seed delinter, the combination with revolving abrading surfaces, and a casing therefor having an opening therein, of an air flume in communication with said opening, a cylinder having a perforate pe-

riphery stationed in said air flume, and journaled with a portion of its periphery projecting through the opening in the casing, a pivoted guard plate stationed within the air flume, and extending downward within the casing, said guard plate being provided with a V-shaped bend to prevent escape of seed between the edge of the opening in the casing and the periphery of the lint removing cylinder, and means for causing said guard plate to bear against the periphery of said cylinder, substantially as described.

In testimony whereof I affix my signature in presence of two witnesses.

JAMES J. FAULKNER.
